UNITED STATES PATENT OFFICE.

WILLIAM H. CALEY, OF DENVER, COLORADO, ASSIGNOR OF ONE-HALF TO
FRED G. FOLSOM, OF BOULDER, COLORADO.

AUTOMATIC SAFETY DEVICE FOR CARS.

SPECIFICATION forming part of Letters Patent No. 710,423, dated October 7, 1902.

Application filed February 10, 1902. Serial No. 93,462. (No model.)

To all whom it may concern:

Be it known that I, WILLIAM H. CALEY, a citizen of the United States, residing in the city of Denver, county of Arapahoe, and State of Colorado, (whose post-office address is No. 408 Ernest & Cranmer Building,) have invented a new and useful Automatic Safety Device for Cars, of which the following is a specification.

10 My invention relates to passenger-carrying cars and similar conveyances which are either provided with or are tributary to power-propelling means and controlling means therefore for starting, stopping, and advancing the car.

15 The invention consists in providing a safety device for preventing accidents to the entering and departing passengers of the car by preventing the starting of the car when any 20 passenger is stepping upon the steps of the car and may therefore be partly on the car and partly on the ground.

Some of the objects of the device are, first, to provide the car or other means of conveyance with automatic means for maintaining the same stationary until persons entering or leaving it have either completely entered or have fully alighted from it and are thus out 30 of a dangerous position partly or wholly upon the steps thereof; second, to provide automatic means to prevent any increase of speed of such car while a person is on its steps, even though such person mounted them while the car or vehicle was in motion, thus permitting 35 persons at their own risk to board and alight from the same or to remain upon the steps thereof while it is in motion, but preventing any increase in the speed of said car over and above that of which the risk was assumed.

40 by the persons when they mounted the steps; third, to provide a positive means whereby the conductor may prevent the motormen from starting the car when danger arises of which the motormen is unaware, as when a vehicle 45 or pedestrian in the street would be caught by some after portion of the car which is out of the range of vision of the motormen—as, for instance, the rear steps—and, fourth, to remove all possibility of negligence on the 50 part of the motormen or other person controlling the movements of the car in starting

or suddenly increasing the speed of the same while persons are in dangerous positions upon its steps.

The term "car" or "power-driven car" will be here understood to mean one that is itself provided with motive means or is in a train with a car or other conveyance that is provided with such motive means.

I do not wish to limit myself to the exact construction shown in the drawings, as it is evident that any suitable mechanical connections from depressible steps to a stop for the controller-shaft will be effective to provide the safety desired.

Of the several views of the drawings, Figure 1 is a transverse sectional elevation through the front platform of a motor-car provided with my improved safety device, the same being on line Z Z of Fig. 2. Fig. 2 is a plan view, on a reduced scale, of the lower part of such a car below line X X of Fig. 1, showing particularly the rock-shaft in connection with steps and controller-shafts at both ends of the car. Fig. 3 is a detached elevation of the lower end of the controller-shaft and adjacent parts at the opposite end of the car from that shown in Fig. 1. Fig. 4 represents a modified form of construction of the step-supports and connections to the ratchet on the controller-shaft. In Fig. 1 different means are shown upon the right and left sides of the car for connecting the lower step with the rock-shaft of the safety device. In Fig. 2 dotted lines represent the location of the car body or frame. Fig. 5 is a perspective view of portions of the rock-shafts of adjacent cars in a train and shows a means of connecting the safety device of a trailer-car with that of a motor-car.

Similar characters designate like parts in the several views.

The controller-shaft A represents the means for turning on and off the current of an electric car, or of setting and loosening the grip of a cable-car, or of regulating any other means used for propelling a car.

It is immaterial in this invention what the power means is, the significant fact being that the power used may be applied to start the car and increased to accelerate it by rotation of the shaft A in one direction and be re-

duced to slow down or cut off to stop the car by rotation of the same in the opposite direction.

The automatic safety device begins with a 5 notched member, which is preferably a disk or wheel provided with a series of ratchet-teeth, as the ratchet-wheel B, which is represented as being fixedly secured to the lower part of the controller-shaft A. The second 10 member of the device is a pawl C, which is adapted to engage the ratchet-teeth of the wheel B and is preferably pivotally supported in any desirable manner, as upon a rock-shaft D, which is preferably supported in bearings secured to the frame of the car, as bearings E. The direction of this rock-shaft D is approximately longitudinal of the car, to be substantially parallel with the steps at the sides of the car; but its direction may be 15 somewhat diagonal to accommodate it to the position of the controller-shafts at the opposite ends of the car.

Fixedly secured upon the rock-shaft D are upward-extending arms F and downward-extending arms F', and these arms may be located at any desired part of the shaft to suit connecting the same with the car-steps. The rock-shaft D is also provided with a member having a pawl-disengaging lug G and a pawl-engaging lug G', and to the latter is fixedly secured a spring G², which bears on the pawl C and yieldingly presses the same into engagement with the teeth of ratchet-wheel B upon the rock-shaft D being tipped appropriately in the direction of the arrow. The spring G² allows the ratchet-wheel B to turn freely in the direction to shut off power; but the pawl prevents its turning in the direction to apply power when the rock-shaft is tipped 30 to cause the engagement of the pawl. Upon tipping the rock-shaft D in the opposite direction the pawl C is forcibly disengaged from the ratchet-wheel B by the lug G. The member having the arms F and F' may be 35 formed integral with the member having the lugs G and G', and it is so represented in the drawings.

An essential feature of the device is making some or all of the steps of the car 40 pressible in order that their being stepped upon may cause sufficient movement to operate the pawl C, and the steps may be mounted in any desirable manner to be slightly elevated when no person is on them by any yielding force, as by a spring or weight. Suitable stops limit the upward-and-downward movement of the steps, which is slight.

One manner of mounting the steps is shown in Figs. 1 and 2 of the drawings and embodies supports H, which are fixedly secured to the car-body as may be desired, and these supports H are provided with holes adapted to receive the ends of shafts I, which form pivot-bearings for the steps J. Fixedly secured upon the shaft I are horizontal arms K, to which the steps J are secured, as may be desired. One of the arms K of each step is

provided with an upright extension K', which is connected with the arms F or F' of the rock-shaft in any desirable manner, as by the 70 rods L. The steps of one side of the car are connected with the upward-extending arms F and those of the opposite side with the downward-extending arms F', that the rock-shaft D shall be tipped in the same rotary 75 direction when any step is depressed.

Where there is more than one step at any one place of entrance of the car and it is desired to have both steps operate the pawl C, they may both be connected directly with the 80 arms of the rock-shaft, as by the rods L and L' in the left side of Fig. 1, or the two steps may be connected together so as to operate as one, as by means of the arms J' and connecting-link J², and then one of the pair of 85 steps connected to the rock-shaft, as by the rod L in the right side of Fig. 1. The essential feature is that all steps or all desired steps shall be connected directly or indirectly with the rock-shaft D to cause the engagement of the pawl C with the ratchet-wheel B when such steps are depressed, as by being stepped upon.

In Figs. 1 and 2 the steps are represented as being elastically sustained in their upper 95 positions against stops H' in a collective manner by means of a compression-spring M, acting upon an arm M', which is fixed upon the shaft D, the steps being raised because of their being connected with the shaft D when it 100 is retracted to its normal position, as shown. Instead of this collective means of sustaining the steps individual step-springs may be used, if deemed more expedient. The steps are sustained against being depressed beyond 105 the proper horizontal position by means of the stops H², which are formed integral with or secured to the supports H.

Another form of mounting for the steps J and of connections to the pawl engaging with ratchet-wheel B is shown in Fig. 4, in which H³ is a support secured to the car-body and is provided with a pivot-joint at N, and there is preferably one of these supports H³ at each end of each pair of steps. The steps J 110 and the shaft I are preferably rigidly secured to suitable end pieces H⁴ and swing as a whole in the pivot-joint N, the downward and inward swinging movement of the steps being limited by the stop H⁵ striking the support H³. In this form the pawl O is pivotally mounted upon a depending arm P, which is fixed upon the rock-shaft D, and the pawl is provided with an inclined face S, which rests upon a projection T of the bearing for 115 the rock-shaft, and this inclined face causes the free end of the pawl to be raised out of engagement and lowered into engagement as the rock-shaft D is tipped. A connection Q from the step end piece H⁴ to the depending arm P causes them to swing simultaneously, and consequently the pawl O is thrown into 120 operative position by the depression of the steps, as before described. A suitable stop

limits the outward and upward movement of the swinging step, as shown at H⁶. A compression-spring R tends to sustain the steps and pawl in their inoperative position, as shown. 5 In this form gravity causes the engagement of pawl O with ratchet-wheel B, and hence the ratchet may turn backward freely, as before.

The two controller-shafts at the opposite ends of the car are preferably provided with oppositely-disposed ratchet-wheels, as shown in Figs. 1, 2, and 3, that for one end of the car preferably facing upward, as shown in Fig. 1, and that for the opposite end of the 15 car facing downward, as shown in Fig. 3, that the rock-shaft D may be located approximately at the center of the car and be operative to throw the pawls out at both ends of the car when tipped in one direction, and vice 20 versa.

An emergency-release is desirable for use with this safety device and is preferably some convenient means of raising the pawl C or O to allow the motormen to speed the car in case 25 of danger—as, for instance, in case of a rapidly-approaching car crossing the track or in case of a runaway team threatening to collide with the car. In Fig. 1 a simple means of so raising the pawl C is shown and consists of 30 a plunger U, which is slidably mounted in the car-platform for vertical movement, the plunger being adapted to be depressed by the foot of the motormen, whereupon it strikes an extension C' of the pawl C, which it depresses, 35 and consequently raises the operative end of the pawl. A retracting-spring U' returns the plunger U to its upper position free from the pawl. It will be apparent that in case of an emergency the motormen may step on the 40 plunger U, and thereby throw the safety device out of operation, that he may speed the car notwithstanding persons may be at the time upon the steps. This emergency-release is preferably made so as to not be capable of 45 being latched or otherwise fastened in a position to hold the pawl out of action, for the reason that an important object of the safety device is to have it substantially always in operation in order to protect the passengers 50 from accident and the car company and its employees from liability. The application of the emergency-release is optional with the car company, and its use may be made dependent upon the nature of the dangers to 55 which any particular line is subject.

In Fig. 5, D D are portions of rock-shafts of adjacent cars, as a motor-car and a trailer, and these are made to tip in unison by means of a loosely-suspended shaft preferably 60 occupying a position below the coupling device of the cars. This suspended connecting-shaft D² is shown formed with T-shaped ends, each extremity of which has a horizontal hole for the reception of the lower end of a suspension hook or link D³. The rock-shafts D are each provided with a horizontal arm, provided, preferably, with similar horizontal

holes D⁴, into which the upper end of the hooks D³ are inserted. The lower end of these hooks are so shaped as to be capable of 70 disengagement when desirable to separate the cars by swinging the connecting-shaft D² far forward or rearward. Yet the hooks are effective to cause one shaft D to tip when the other shaft D is tipped, and hence stepping 75 on the step of the trailing car will operate the safety device of the motor-car to which it is connected. The suspended connection, as shown, allows the necessary freedom of the coupled cars in going over uneven track or 80 around curves.

Having thus described my invention, I claim as new and desire to secure by Letters Patent—

1. In a power-driven car, the combination 85 with a power-controlling shaft, of yielding steps at the entrances of said car; and connecting means between said controlling-shaft and said steps, in position and adapted to lock said shaft against being turned to apply 90 power when any of said steps are depressed.

2. In a power-driven car, the combination with a power-controlling shaft, of depressible steps at the places of entrance of said car; a series of ratchet-notches upon a member secured upon said controlling-shaft; and a pawl 95 in position and adapted to engage said ratchet-notches, and operatively connected with said steps.

3. In a power-driven car, the combination 100 with depressible, yielding steps at the entrances of the car, of retracting means for raising said steps; power-controlling means adapted to apply or increase the motive power of said car by being moved in one direction, 105 and to reduce or cut off such motive power by being moved in the opposite direction; and connecting means in position and adapted to lock the said power-controlling means against movement in the direction to apply power, 110 while permitting movement in the direction to cut off power, when said steps are depressed.

4. In a power-driven car, the combination 115 with depressible steps at the entrances of the car, of a controller-shaft adapted to govern the application of power to propel the said car; a ratchet-wheel secured upon said controller-shaft; a pawl mounted for engagement with said ratchet-wheel; and a rock-shaft 120 operatively connected with said steps and with said pawl, whereby the engagement of the said pawl will be caused by the depression of said steps.

5. In a power-driven car, the combination 125 with depressible steps at the entrances of the car, of a controller-shaft provided with a ratchet-wheel; a rock-shaft operatively connected with said steps; a pawl pivotally mounted on said rock-shaft and adapted to 130 engage said ratchet-wheel; positive means carried by said shaft for disengaging said pawl from said ratchet-wheel; and yielding means carried by said rock-shaft for moving

said pawl into engagement with said ratchet-wheel.

6. In a power-driven car, the combination with depressible steps at the entrances of the car, of limit-stops and elastic lifting means for said steps; a power-controller provided with a ratchet member; and means substantially as specified, for locking the said controller against movement to apply power.
- 10 7. In a power-driven car, the combination with depressible steps, of a controller-shaft provided with a ratchet-wheel; a pawl for engagement with said ratchet-wheel, and connected with said steps; and an emergency-release for said pawl.
- 15 8. In cars moved by power and governed by a controller having a series of ratchet-teeth, depressible steps at the entrances of

said cars; a pawl in position and adapted to engage said ratchet-teeth; connections between said steps and said pawl embodying a rock-shaft upon each of said cars; and a connecting-shaft for said rock-shafts, suspended from two points of each of said rock-shafts, and adapted to cause them to tip in unison, 25 to operate the said pawl from the steps of the trailing car.

In testimony whereof I have signed my name to this specification, in presence of two subscribing witnesses, at Denver, Colorado, 30 this 6th day of January, A. D. 1902.

WILLIAM H. CALEY. [L. S.]
